Primary Examiner — John Windmuller*Assistant Examiner* — John R Yeh(74) Attorney, Agent, or Firm — Irina Hass(57) CLAIM

The ornamental design for a cleaning cloth, as shown and described.

DESCRIPTION

FIG. 1 is a perspective view showing the new design for a cleaning cloth;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the figures represent features of the cleaning cloth that form no part of the claimed design.
